* cited by examiner

Primary Examiner—Prabhakar Deshmukh*Assistant Examiner*—Elizabeth J Oswecki*(74) Attorney, Agent, or Firm*—Thomas & Raring, P.C.(57) CLAIM

The ornamental design for a detachable charm for footwear, as shown and described.

DESCRIPTION

FIG. 1 is a top, front, right side perspective view of a detachable charm for footwear showing my new design;

FIG. 2 is a front view thereof;

FIG. 3 is a rear view thereof;

FIG. 4 is a right side view thereof, the left side view being identical; and,

FIG. 5 is a top view thereof, the bottom view being identical.

The broken line showing of a logo and sandal in FIGS. 1 and 2 is included for the purpose of illustrating only and forms no part of the claimed design.

1 Claim, 2 Drawing SheetsFIG. 1

FIG. 2FIG. 3*FIG. 4*FIG. 5
